DESIGN FOR A VANITY CASE

Raymond Loewy, New York, N. Y., assignor to
Elizabeth Arden Sales Corporation, New York,
N. Y., a corporation of Delaware

Application March 15, 1934, Serial No. 51,060

Term of patent 3½ years

To all whom it may concern:

Be it known that I, RAYMOND LOEWY, a citizen of France, resident of New York, in the county and State of New York, whose post office address is 500 Fifth Avenue, New York, N. Y., have invented a new, original, and ornamental Design for Vanity Cases, of which the following is a specification, reference being had to the accompanying drawing, forming part thereof.

The figure is a perspective view of a vanity case, showing my new design.

I claim:

The ornamental design for a vanity case, as shown.

RAYMOND LOEWY.
